UNITED STATES PATENT OFFICE.

THEODOR FOTCHUK, OF TORONTO, ONTARIO, CANADA.

SHOE-CLOSURE.

1,390,991.

Specification of Letters Patent. Patented Sept. 20, 1921.

Application filed May 7, 1921. Serial No. 467,617.

To all whom it may concern:

Be it known that I, THEODOR FOTCHUK, a citizen of the Ukraine, residing at Toronto, Province of Ontario, and Dominion of Canada, have invented certain new and useful Improvements in Shoe-Closures, of which the following is a specification.

The present invention relates to improvements in shoe closures, particularly closures 10 for lace shoes, and it is the principal object of the invention to provide auxiliary means for facilitating the lacing operation.

A further object of the invention is to provide an auxiliary lacing means which permits the securing of the shoe laces when 15 properly tightened to close the shoe.

Another object of the invention is the provision of a suitable perforated plate for properly holding the ends of the laces during 20 the lacing operation, and of means for quickly and conveniently unlacing a shoe.

Other objects and advantages of my invention will become more fully apparent as the description thereof proceeds and will 25 then be specifically pointed out in the appended claims.

In the accompanying drawings, forming a material part of my invention—

Figure 1 shows in side view part of a 30 shoe equipped with the auxiliary lacing means constructed according to the present invention.

Fig. 2 is a view similar to Fig. 1 seen from the opposite side of the shoe.

Fig. 3 shows in side elevation the auxiliary lacer separated from the shoe.

Fig. 4 is a lateral edge view of the same.

Fig. 5 is a top plan view of a lock used in connection with the lacer.

Fig. 6 is a longitudinal vertical section 40 through the lock, Fig. 5.

Fig. 7 is a transverse section through the lock, and

Fig. 8 shows in detail view a lace holding 45 or anchoring plate.

In the drawings, the shoe 10 of any ordinary well known shape and material is closed by means of the customary lace 11 passed through the usual eyelets 11'. The end of 50 the lace is held underneath the lowermost eyelets 11' within the shoe by a plate 12 provided with openings 13 through which the lace is threaded in the manner indicated in Fig. 8.

The lace 11 is then threaded in the manner 55 illustrated in Fig. 1 through the eyelets 11'

of the shoe and the eyelets in an auxiliary lacing member 14 provided with eight holes 15 arranged as indicated in Fig. 3.

To the end of member 14 is secured a rack 60 plate provided with teeth 16, adapted to be introduced into a lock casing 17 through an opening in the upper end wall of the same.

This casing is secured to the shoe by means of a strap 18 in the manner illustrated in 65 Figs. 2 and 4, and its free end is sewed to the uppers of the shoe at the seam 19 thereof.

The casing 17 is provided on its top with a sliding plate 20 and its cover has a longitudinal slot 21 in which travels a rivet 22 on 70 the sliding plate 20.

To the underside of the cover plate of the casing a leaf spring 24 is secured at one of its ends by means of rivets 25, and the other end of this spring is formed into a hook 26. 75

The spring is normally kept out of engagement with the teeth 16 by resting upon a flange 23 at the lower end of the rivet 22, and it will be clear that by the suitable displacement of the rivet in the slot 21 the spring 80 will engage the teeth 16 and lock the auxiliary member 14 in its lace tightening position after it has been guided around the rear part of the shoe as indicated in Fig. 1.

The upper end of the lace is guided 85 through a plate 27 in a similar manner as described above with respect to plate 13 and is then tucked under the tongue of the shoe.

The device operates as follows:

Assumed the shoe is unlaced, it will then 90 only be necessary to draw the end of the auxiliary member 14 upward to tighten the lace and guide the member 14 thereafter around the rear part of the shoe and to introduce its end part with the teeth 16 into the 95 lock casing 17.

When now the rivet 22 is displaced in the longitudinal slot 21 in such a manner that its flange 23 will release spring 24, the hooked end 26 of this spring will engage the teeth 16 and thus lock the member 14 in its lace 100 tightening position. To open the shoe the operation need simply to be reversed.

Having thus described my invention, what I claim is:

1. An auxiliary shoe lacing device of the class described comprising a movable perforated member, through the perforations of which the laces are threaded, a toothed plate at one end of said member, a casing secured 110 to the shoe and means within said casing for locking said member in its lace tightening

position by engagement with said toothed plate and means for firmly holding the lace ends.

2. An auxiliary shoe lacing device of the class described comprising a movable perforated member through the perforations of which the shoe lacing is passed, a perforated casing sewed to the opposite side of the shoe, a toothed plate at one end of said member adapted to be introduced into said casing, a movable means within said casing adapted to be engaged and disengaged from said toothed plate for securing and releasing said member, and perforated plates for securing 15 the ends of the laces.

3. An auxiliary shoe lacing device of the class described comprising a movable perforated member through which the shoe laces

are passed on one side of a shoe, a casing secured to the shoe at the opposite side thereof, a slotted cover for said casing, a flanged rivet traveling in the slot of said cover, a toothed plate at the end of said member adapted to be introduced into said casing, a leaf spring normally resting upon the flange 20 of said rivet above said toothed plate, and adapted to engage with its hooked end the teeth of said plate upon the displacement of said rivet in the slot of the cover, means for securing said casing to the shoe at the seam 25 of the shoe uppers and means for securing the ends of the laces. 30

In testimony whereof I have affixed my signature.

THEODOR FOTCHUK.
